UNITED STATES PATENT OFFICE.

WALTER ELLWOOD ALLEN, OF WASHINGTON, DISTRICT OF COLUMBIA.

DESIGN FOR A PAPER-KNIFE.

SPECIFICATION forming part of Design No. 22,278, dated March 14, 1893.

Application filed February 17, 1893. Serial No. 462,775. Term of patent 3½ years.

To all whom it may concern:

Be it known that I, WALTER ELLWOOD ALLEN, a citizen of the United States, and a resident of Washington, in the District of Columbia, have invented and produced a new and original Design for a Paper-Knife, of which the following is a specification.

The leading feature of my design consists in a knife in which the representation of a Grand Army badge forms the handle, a knife blade forming the cutter of the same.

In order that my invention may be fully understood I will proceed to describe it with reference to the accompanying drawing which represents a front view of my design for a paper knife.

1 is the handle of the paper knife and 2 the

blade of the same. The handle consists of the representation of a flag 3, a pendant or star 4, and a guard 5; the latter being ornamented with a representation of crossed cannon 6, a saber 7, and an eagle 8. On the blade are represented the corps badges of the United States Army. The whole is designed as a Grand Army of the Republic souvenir.

Having thus described my invention, the following is what I claim as new therein and desire to secure by Design Letters Patent:

The design for a paper-knife substantially as herein shown and described.

WALTER ELLWOOD ALLEN.
